COMBINATION CABINET AND DRESSING TABLE

Irwin Brill, New York, N. Y.

Application March 23, 1953, Serial No. 343,857

6 Claims. (Cl. 312—226)

This invention relates to a combined cabinet and dressing table including clothes rack means, shoe support means, shirt housing means, mirror means and tie rack means.

An object of this invention is to provide in kit form mass producible means which can be readily assembled by an unskilled person into a combined cabinet and dressing table.

Another object of this invention is to provide an improved compact combined cabinet and dressing table wherein wood, plastic and the like is largely used as a substitute for metal.

A further object of this invention is to provide a combined cabinet and dressing table with means affording the storage of items constituting wearing apparel within a minimum of space and wherein said items are readily available.

Still another object of this invention is to provide a device which is a combined cabinet and dressing table and includes displaceable elements for storing items constituting wearing apparel and for permitting access to the latter even while the device is being used as a dressing table.

Yet another object of this invention is to provide a combined cabinet and dressing table which occupies a minimum amount of floor space and wherein items which constitute wearing apparel are separately, accessibly and compactly stored so as to avoid soiling of the latter.

With the above and other objects in view, the invention will be hereinafter more particularly described, and the combination and arrangement of parts will be shown in the accompanying drawings and pointed out in the claims.

Reference will now be had to the drawings, wherein like reference numerals designate corresponding parts throughout the several views, in which:

Fig. 1 is a perspective view of a combined cabinet and dressing table constructed in accordance with this invention.

Fig. 2 is a top plan view of the combined cabinet and dressing table.

Fig. 3 is a front elevation of the combined cabinet and dressing table with the front curtain removed in order to expose the interior of the cabinet.

Fig. 4 is a side elevation of the combined cabinet and dressing table with the curtains removed.

Fig. 5 is a fragmentary side view of the combined cabinet and dressing table on a larger scale showing the details of the mirror support, curtain support, and of the hinge means for the shirt housing closure, as well as the details of the assembly of the table top to the legs.

Fig. 6 is a fragmentary front view of the combined cabinet and dressing table on a larger scale showing the details of the mirror support and of the drape support.

Fig. 7 is a perspective view of the shoe rack constructed according to the invention and of the means for assembling said shoe rack to one of the legs of the combined cabinet and dressing table.

Fig. 8 is a view of another modification of the means

2

for assembling the shoe rack shown in Fig. 7 to one of the legs of the combined cabinet and dressing table.

Fig. 9 is a perspective view of a modified shoe rack and of the corresponding means for assembling the latter to one of the legs of the combined cabinet and dressing table.

Fig. 10 is an enlarged detail view of the ball detent means which can be used in conjunction with the mirror support for maintaining the mirror in a predetermined position.

Fig. 11 shows a fragmentary view of a modification of the invention wherein the mirror and the tie rack or clothes rack are separately mounted for relative displacement with respect to the combined cabinet and dressing table.

Fig. 12 shows a fragmentary top plan view of the modified form of the invention shown in Fig. 11.

In the illustrated embodiments of the invention, a table top 20 is supported by a plurality of spaced legs 21. Depending from the periphery of the table top are curtains, or drapes, 22, 23 supported in a manner that will be presently explained.

In accordance with the present invention, a specific embodiment for supporting the curtains 22 and 23 comprises grooves 25 located substantially along the perimeter of the lower portion 24 of table top 20. In Figures 5 and 6 the support elements 26 are shown in assembled position within grooves 25. Elements 26 are slidably guided and retained within grooves 25 and these elements are provided with curtain supporting hooks 27. Elements 26 are positioned in grooves 25 by appropriate means, not shown, which may include spring means urging outwardly the ends of the elements. Alternatively, the grooves may be extended to the periphery of table top 20 and the elements may then be inserted in grooves 25 in obvious manner.

As shown in Figures 4 and 5 table top 20 is provided with at least one depending lug 40, located at each of the corners thereof. Each of legs 21 may either be made from a tubular body having any appropriate cross section determined by the cross section of the corresponding lug 40 or provided with a cavity 41 at the end thereof. The inner dimensions of each of legs 21 or of cavity 41 permit the insertion of depending lugs 40.

When assembling table top 20 and legs 21, the legs 21 may be retained on the lugs 40 by a friction fit which can be obtained in any manner as a result of cementing, hammering, force fitting, or by any heat treatment including welding.

Now referring to Figures 1 and 4 table top 20 includes a plurality of sections 50, 51, 52 at least one of which is hinged. Sections 51 and 52 are formed by cutting away portions of table top 20 which was originally made from a solid piece or slab of wood, plastic and the like.

Each of sections 51 and 52 is provided with handle means 58, 59, whereby the sections may be manually displaced.

Section 51 is hingedly secured at 53, 53' to section 50 and may be pivoted outwardly to the dotted line position shown in Fig. 5. A shirt housing 54 is provided with a trapezoidal section or a section similar to the conic section obtained in cutting a truncated oblique cone by a plane perpendicular to the base thereof and passing through the imaginary apex thereof. This section is advantageous in permitting the storage of a maximum number of shirts within a compact space. The housing 54 is secured to the lower portion 24 of section 50 and below section 51. The shirt housing 54 includes means 55 which consists either of pins, tacks and the like for permanently securing the housing 54 to section 50 or of projections on the ends of the housing 54 cooperating with guide rails slidably receiving said projections to

thereby permit removal of the housing 54 from section 50 upon displacement of the housing relative to said section.

Section 52 is provided with standards 56 having spring urged ball detent means 69 illustrated in Fig. 10 and cooperating with support means 60 in order to adjustably support section 52 between an upper position wherein mirror 70 is fully exposed and a lower position wherein the surface of section 52 lies in a plane common with the plane in which section 50 extends. Support means 60 includes tubular elements 61 provided with oblique openings or indentations 62 adapted to receive ball detent means 69 and bracket means 63 adapted to be secured by bolts, lugs, cementing means, welding and the like, to the legs 21 and to elements 61 for fixedly supporting each of said tubular elements 61 to at least one of said legs 21. Cam projection 64 is formed on tubular element 61. Standards 56 are interconnected by transverse bar 65 supporting substantially L shaped bodies 66 each having one leg secured to a mirror body 70, the other leg being secured to bar 65 for pivoting movement about said bar. If desired, spring means, not shown, may be mounted on bar 65 and about mirror 70 or bodies 66 to thereby urge mirror 70 to any predetermined angular position relative to the vertical when section 52 has been raised. The portion of bar 65 between bodies 66 forms a rack for supporting ties or if desired clothes hangers having their longitudinal axis parallel to the longitudinal axis of bar 65 so that overcoats may also be stored in the combined cabinet and dressing table.

Cam projection 64 is engageable with mirror 70 for moving the latter so that it is substantially vertical when section 52 is in its lower position. A raised portion 67 is provided on at least one of standards 56 in order to limit the angular deviation or inclination of said mirror with respect to the vertical when section 52 is in its upper position.

Substantially U-shaped rod 73 is suitably secured to section 50. Rod 73 forms clothes supporting means or a rack and support for a plurality of hangers for articles of clothing. If desired, rod 73 may be longitudinally displaced.

Protector body 74 may be made from any appropriate transparent or opaque material such as plastic, Celluloid, fabric and the like, and is secured at one end 75 to section 50 while the other end includes means 76 attachable to each of legs 21. The interior of body 74 and surface 24 of section 50 define a chamber or space 77 within which a shoe rack 80 is supported.

Referring to Figures 4 and 7 the cantilever shoe rack 80 includes a pair of bars 81, 82, interconnected by a plate 83 or the like. Bar 82 is provided with bifurcated extremities 85. Channel bars 86 which are suitably secured to legs 21 include arms 86' spaced from legs 21 so as to receive the extremities 85 of bar 82 and thereby support the shoe rack 80 on said legs.

Referring to Fig. 8 bar 82 may be provided with a reduced end portion 85' instead of the bifurcated extremities 85 and leg 21' is provided with an opening 87 adapted to receive end portion 86 for securing the shoe rack to said legs.

A modified shoe rack is shown in Fig. 9 and includes a pair of bars 81', 82', joined by L-shaped rods 83', 84, provided with reversely bent extremities 88, 89 adapted to be seated in a notch 90 and a groove 91, respectively, provided on leg 21".

Figures 11 and 12 show a modified form of the invention wherein sections 92 and 93 have been substituted for section 52, and hollow elements 94 have been substituted for tubular elements 61. Hollow elements 94 are each provided with at least a pair of perforations 95, 96, having their axes lying in a perpendicular plane. However the axes of perforations 95, 96 may each extend along either a vertical line or an oblique line and they need

not be parallel or coextensive. Standards 97, 98 which are provided on sections 91, 92 are received within perforations 95, 96, respectively. The standards 98 are also interconnected by means 65, 66 for supporting mirror 5 70 in the manner shown in Fig. 6.

Transverse rod 99 joints standards 97 and forms another rack or support for garment hangers or for ties. Handle means 59, 59' is similar to that already described and may be grasped to lift separately the sections 92, 93. The ball detent means shown in Fig. 10 is provided in elements 94 and permits adjusting the height of the mirror support and of the tie or garment rack portion. For instance, when an overcoat is supported on rack 99 by a garment hanger the section 92 15 is maintained in raised position to thereby avoid soiling the bottom of the overcoat. The raised position of section 92 does not interfere with the raising of section 93. If desired, section 93 can cooperate with section 92 when both are raised so that the overcoat is also 20 protected by the mirror. In addition the ends of section 92 adjacent standards 97 may each be provided with a plate, not shown, whereby the articles of clothing supported in rack 99 cannot be seen from the sides of the combined cabinet and dressing table and the articles of 25 clothing are better protected against soiling.

Obviously, the standards and the legs may be made of wood, metal, plastic and the like. The legs 21 may further be provided with caster wheels, not shown, to facilitate moving the combined cabinet and dressing table.

30 The shirt housing 54, clothes support rack 73 and protector body 74 are positioned below table top 20 so that garment hangers supported by rack 73 will fully occupy the space between housing 54 and body 74 thereby permitting positioning the articles of clothing supported by said hangers so that the bottom of the articles is well above the floor and the articles may be removed upon displacing the curtain 23 on either side of the combined cabinet and dressing table or upon displacing the curtain 22.

35 40 Although a plurality of embodiments of the invention have been described and illustrated, it will be understood that various changes and modifications can be made therein without departing from the spirit of the invention as defined by the appended claims.

45 What is claimed is:

1. A combined cabinet and dressing table for housing wearing apparel including coats, suits, shoes, shirts and the like, comprising a plurality of supporting legs, a table top directly supported by said legs and including 50 a fixed frame section including openings and a plurality of spaced independently movable sections mounted within said openings for movement between an operative position and a second position for closing said openings whereby said table top is provided with a flat continuous surface, first means including mirror means, rack support means, and a first of said movable sections, said first means being connected to a portion of said legs for slidably mounting said mirror and rack support means between said operative and second positions, second means including a second of said movable sections and housing means both connected to said fixed frame section for housing said shirts, third means connected to said fixed frame section and to the remainder of said legs for defining a first space adapted to receive said shoes, and first rack means supported by said fixed frame section and positioned between said second and third means for supporting said suits, whereby said wearing apparel is independently and compactly housed within said cabinet and dressing table.

70 2. A combined cabinet and dressing table according to claim 1, wherein said first and said second sections are each provided with means for manually displacing said last mentioned sections, whereby said mirror means is movable to a position above said table top and said

shirts may be withdrawn from said second means upon displacement of said second section.

3. A combined cabinet and dressing table according to claim 1, wherein said second means and said third means are each provided with a trapezoidal cross-section and the adjacent sides thereof define a substantially triangular space adapted to receive the shoulder and neck portions of said units supported on said first rack means.

4. A combined cabinet and dressing table according to claim 1, comprising fourth means connected to said third means for movement relative thereto and including second rack means, whereby said second rack means is movable independently of said third means and said last mentioned rack means is adapted to support overcoats.

5. A combined cabinet and dressing table according to claim 1, comprising cantilever rack means for supporting shoes, said cantilever rack means being supported within said first space and cooperating with said third means to thereby prevent soiling of said suits when said shoes are placed within said third means and on said 20 cantilever rack means.

6. A combined cabinet and dressing table according to claim 5, wherein said legs are provided with hollow portions, said table top is provided with a plurality of lugs and said cantilever rack means includes projecting extremities, said projecting extremities and said lugs being receivable within said hollow portions to thereby secure said table top, said cantilever rack means and said legs in assembled position.
